LOOSE LEAF BINDER

Filed July 13, 1933

UNITED STATES PATENT OFFICE

2,000,184

LOOSE LEAF BINDER

Adolph G. Lotter, Milwaukee, Wis., assignor to
Stationers Loose Leaf Company, Milwaukee,
Wis., a corporation of Wisconsin

Application July 13, 1933, Serial No. 680,223

3 Claims. (Cl. 129—9)

This invention relates to certain new and useful improvements in loose leaf binders and refers more particularly to ring binders of the type forming the subject matter of Letters Patent No.

5 1,758,327, issued to Adolph G. Lotter, May 13, 1930.

It is an object of this invention to improve and simplify the means for attaching the covers and back of the binder to the ring carrying mechanism.

10 Another object of this invention is to improve the general appearance of the binder.

More specifically, it is an object of this invention to provide a channel-shaped metal back plate having covers attached thereto and fitting over the ring carrying and shifting mechanism to provide a neat protecting enclosure therefor.

With the above and other objects in view which will appear as the description proceeds, 20 my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a perspective view looking at the 35 under side of the ring carrying mechanism showing the ring sections separated, part of the mechanism being broken away;

Figure 2 is a perspective view of the back and adjacent portions of the covers; and

40 Figure 3 is a cross section view through the complete binder.

Referring now more particularly to the accompanying drawing in which like numerals indicate like parts throughout the several views, the numeral 5 indicates generally the ring carrying and shifting mechanism and the numeral 6 designates the back and cover assembly.

The ring carrying mechanism consists of an inverted channel-shaped base plate 7 on the top side of which two ring carrying plates 8 are mounted for transverse sliding movement. These plates 8 carry substantially semi-circular ring sections 9, which when the plates are brought together, form complete rings as illustrated in Figure 3.

The opposite ends of the base plate 7 are turned over the ends of the plates 8 as at 10 to retain the plates 8 assembled with the base plate.

Longitudinally slidably mounted between the side flanges 11 of the base plate is a ring shifter bar 12. This bar has a plurality of cam slots 13, each having a straight and an inclined portion in which studs 14 fixed to the plates 8 are received.

10 The studs 14 also pass through transverse slots 15 in the base plate. Hence, upon longitudinal shifting of the bar 12, the plates 8 are moved laterally to engage and separate the ring sections 9. To facilitate shifting of the bar 12, a 15 handle 16 is formed on one end thereof to project beyond the adjacent end of the base plate.

10 As will be readily apparent from the disclosure, the engagement of the studs 14 in the straight portions of the slots 13 precludes accidental separation of the ring carrying plates, and to prevent accidental shifting of the bar 12, a spring urged friction lock 17 is provided.

This lock may be of any suitable construction 25 and in the present instance, comprises merely a spring plate riveted to the underside of the bar 12 with its upper end extending through an opening in the bar to engage a friction point carried at the outer free end thereof with the 30 undersurface of the base plate 7.

At three longitudinally spaced points, the base plate 7 has counterbored openings 18, two of which lie above the shifter bar 12. To afford access to these two openings 18 from between 35 the shifter bar, the bar has elongated openings 18' (only one of which is shown in view of the fact that the central portion of the mechanism is broken away). Received in the counterbored openings 18 are the outer ends of connecting 40 studs or rivets 19 to secure the ring carrying mechanism to the back and cover assembly 6, the connecting studs or rivets being fixed to the back.

The cover and back assembly 6 consists of a 45 channel member or back plate 20 of relatively thin but stiff metal having side flanges 20' connected by a central web 21. The side edge portions of the web 21 directly inwardly of the flanges 20' are curved as illustrated in Figure 50 3 to reduce the abruptness of the corners and thus add to the appearance of the binder. The rivets 19 are rigidly secured to the web 21 with their heads counter-sunk and flush with the outside surface of the back plate.

Mounted on the rivets 19 are spacing collars 23, which, as illustrated in Figure 3, are recessed to receive the projections of the base plate formed by the counterbore of the openings 18, 5 to positively and securely space the back plate from the base plate. Thus, when the parts are assembled, a rigid connection is established between the two plates.

Prior to assembly, of the back plate and the 10 ring carrying mechanism, the covers 24 are attached to the back plate. The covers are preferably bound with leather or other suitable flexible material which is applied in a single piece glued or otherwise secured at its medial portion 15 to the outer face of the back plate and extended out over backing sheets 25. The backing sheets may be of rigid or semi-rigid material and the marginal edge portions of this flexible binding material are folded over the backing sheets 20 25.

The inner surface of the back plate 20 is covered with a piece of fabric 26 the edges of which extend out over the backing sheets 25 of the covers. The backing sheets are spaced from 25 the edges of the flanges 20' and the fabric 26 is folded down into this space to define hinge joints 27. The inner surfaces of the covers have finishing sheets 28 glued thereto which extend out over the folded edges of the outer covering 30 material and over the fabric 26.

It is to be noted that the channel-shaped back plate is slightly wider than the channel-shaped base plate and that when the units are assembled the base plate nests within the back plate with the flanges of the two members overlapping as shown in Figure 3. In this manner, the ring separating mechanism is completely concealed and protected and inasmuch as the back plate is wider than the ring sections or any 40 other portion of the binder when the sections are closed, the covers extend evenly from the edges of the back thus greatly improving the appearance of the binder and facilitating handling thereof.

45 From the foregoing description taken in connection with the accompanying drawing, it will be readily apparent to those skilled in the art, that this invention affords a simple manner of attaching the back and covers of a ring binder to the ring carrying mechanism and that it improves the appearance of such binders considerably.

What I claim as my invention is:

1. In a loose leaf binder, separable ring sec-

tions, a base plate channel-shaped in cross section, means on the outer face of the base plate to separably mount the ring sections, a back plate channel-shaped in cross section and wider than the base plate, means to connect said plates with the base plate nested in the back plate, mechanism to shift the ring sections disposed in the space between the nested back and base plates, and covers carried by the back plate.

2. In a loose leaf binder, a base plate channel-shaped in cross section, separable ring sections, sidewise shiftable members on the outside face of the base plate to mount the ring sections for movement to and from closed position, a longitudinally shiftable bar underneath the base 15 plate and lying within the hollow thereof, means operable upon longitudinal shifting of said bar to move said ring section carrying members, a back plate channel-shaped in cross section, said back plate being wider than the base plate 20 to extend beyond the sides thereof, means to rigidly connect the back plate to the base plate with the inner face of the back plate facing the base plate and cooperating therewith to form a housing for said longitudinally shiftable member, 25 and covers attached to said back plate.

3. In a loose leaf binder, a base plate channel-shaped in cross section and having transverse slots, separable ring sections, flat sidewise shiftable members on the outside face of the base 30 plate to mount the ring sections for movement to and from closed position, the combined width of said flat sidewise shiftable members being no greater than that of the base plate so that when the ring sections are closed said flat members do not project beyond the base plate, a longitudinally shiftable bar underneath the base plate lying within the channel thereof and having diagonal slots complementary to said transverse slots, means extending through the base 35 plate transverse slots and bar cam slots and connecting said bar with the sidewise shiftable members whereby longitudinal shifting of said bar moves the sidewise shiftable members to open and close the ring sections, a back plate channel-shaped in cross section, said back plate being wider than the base plate to extend beyond the sides thereof, means to rigidly connect the back plate and the base plate in face to face 40 relation to form a housing for said longitudinally shiftable member, and covers carried by said back plate.

ADOLPH G. LOTTER.
